CLAIM

The ornamental design for a game cartridge, as shown and described.

DESCRIPTION

FIG. 1 is a front, top, right perspective view of a first embodiment of a game cartridge showing my new design; FIG. 2 is a rear, bottom, right perspective view thereof; FIG. 3 is a front elevational view thereof; FIG. 4 is a rear elevational view thereof; FIG. 5 is a left side elevational view thereof; FIG. 6 is a right side elevational view thereof; and FIG. 7 is a bottom plan view thereof.

FIG. 8 is a front, top, right perspective view of a second embodiment of a game cartridge showing my new design; FIG. 9 is a rear, bottom, right perspective view thereof; FIG. 10 is a front elevational view thereof; FIG. 11 is a rear elevational view thereof; FIG. 12 is a left side elevational view thereof; FIG. 13 is a right side elevational view thereof; and, FIG. 14 is a bottom plan view thereof.

In the drawings, the broken lines depict portions of the game cartridge and from no part of the claimed design. Dot-dash broken lines define the boundaries of, but not included in, the claimed design.

1 Claim, 7 Drawing Sheets
